UNIVERSAL ELECTRIC CONNECTOR

Garfield Price, Gary, Ind.

Application May 26, 1939, Serial No. 275,978

1 Claim. (Cl. 173—361)

This invention relates to a universal electric connector for extension cords and similar devices, and has for the primary object the provision of an efficient and inexpensive connector 5 which may be readily plugged in or pushed into an electric output of a conventional construction or threaded into an electric output of the screw threaded type and which will provide for safety against electric shocks while being handled in the application and removal thereof from the electric output.

With these and other objects in view, the invention consists in certain novel features of construction, combination and arrangement of parts to be hereinafter more fully described and claimed.

For a complete understanding of my invention, reference is to be had to the following description and accompanying drawings, in which.

20 Figure 1 is a side elevation illustrating a universal electric connector constructed in accordance with my invention.

Figure 2 is a vertical sectional view illustrating the same.

25 Figure 3 is an end elevation illustrating the device with the screw threaded plug portion removed.

Figure 4 is a sectional view taken on the line 4—4 of Figure 2.

30 Figure 5 is a vertical sectional view illustrating the insulated casing of the device.

Figure 6 is a side elevation illustrating the reversible contact supporting plug.

35 Figure 7 is a vertical sectional view illustrating a slight modification of the invention.

Figure 8 is a perspective view illustrating one of the contacts.

Referring in detail to the drawings, the numeral 5 indicates a casing constructed of insulating material and of tubular formation having a portion thereof reduced to form a neck 6 through which is adapted to extend an electric extension cord 7, the conductors 8 of which after entering the casing are provided with 40 coiled portions 9 for the purpose of permitting the conductors to be extended and shortened as desired.

The casing 5 upon the interior thereof and at the enlarged end portion has its internal diameter increased which forms an annular shoulder 45 10 acting as a seat for a removable contact plug 11 of insulated material. Said latter-named end portion of the casing upon opposite sides thereof and upon the interior is provided with ribs 12 50 adapted to have seating relation with grooves 13

formed in opposite walls of the contact plug 11. The contact plug when inserted in the casing has a frictional fit therewith. The contact plug 11 is further provided with oppositely arranged grooves 14 extending from end to end thereof in which are positioned contact elements 15 which project beyond opposite ends of the contact plug 11 and are held within the plug by set screws 16 which further act to secure the electric conductors 86 to the contacts 15. 10

It will be seen by reference to the drawings that the contact plug 11 when seated against the internal shoulder of the casing has the outer end thereof flush with the large open end of the casing with the contacts projecting a selected 15 distance beyond the open end of the casing for connection with a plug-type fitting 17 constructed of insulated material and which includes the usual central contact 18 and the ferrule threaded type contact 19, one of the contacts 15 being electrically connected to the central contact 18 while the other contact 15 is electrically connected to the ferrule type contact 19. It is to be understood that the contacts are 20 insertible in the plug type fitting 17 so that 25 the latter can be easily removed when desired. The plug type fitting 17 permits the connector to be readily adapted into an electric output of the screw threaded socket type. Should it be desired to connect the connector to an electric 30 output having spaced contact receiving sockets of the usual type, the contact plug 11 is removed and replaced in the casing 5 in a reverse position so as to present the other ends of the contacts 15 outwardly of the casing so that 35 they may be plugged into the latter-named type of electric output.

As shown in Figure 7 the contact carrying plug 11 may be constructed of sections, the sections being detachably connected by a tie bolt 40 20. In mounting the contacts 15 in either of the types of contact plugs 11 it is to be understood that the contacts 15 extend through openings provided therefor with the heads of the contact screws 16 lying in the grooves 14 so as 45 to permit the conductors to be connected thereto and also to permit the conductors to extend into the screws without pinching or binding.

From the foregoing description taken in connection with the accompanying drawings, it will 50 be noted that a very simple, practical and durable connector has been provided with an extension cord wherein the connector may be used in conjunction with either the plug-in type or screw threaded type of electric output through 55

a simple rearrangement or adjustment of the contact carrying plug of the device.

It is believed that the foregoing description, when taken in connection with the drawings will fully set forth the construction and advantages of this invention to those skilled in the art to which such device relates, so that further detailed description will not be required.

Having described the invention, I claim:

- 10 An electric connector comprising a casing formed of non-conducting material and including a cylindrical part and a reduced tubular part at one end of the cylindrical part, the other end of the cylindrical part being open and the open end portion being of greater diameter than the rest of the cylindrical portions, the junction of the large diameter part with the other part forming an internal shoulder and oppositely arranged projections formed on the 15 inner wall of the part having the large diameter, a plug having a snug fit in the large part

of the casing and adapted to be removed through the open end thereof, said plug having a pair of longitudinally extending grooves therein for receiving the projections and said plug having a pair of large longitudinally extending grooves 5 therein, both sets of grooves being arranged in the periphery of the plug, a pair of elongated prong forming members having their middle portions inserted in the plug and their end portions projecting from opposite ends of the plug. 10 screws passing transversely into the plug and through the middle portions of the prong forming members, the heads of the screws being located in the middle portions of the large grooves, an electric extension cord passing into the reduced tubular portion and including conductors having coiled portions confined within the cylindrical part of the casing and having their ends entering the large grooves and connected with the screws. 15 20

GARFIELD PRICE.
